Primary Examiner — Austin Murphy(74) *Attorney, Agent, or Firm* — Dunlap Bennett & Ludwig, PLLC; Brendan E. Squire(57) **CLAIM**

The ornamental design for a visor mounted eyewear, as shown and described.

DESCRIPTION

FIG. 1 is a front perspective view of the present embodiment;

FIG. 2 is a front elevation view of the present embodiment;

FIG. 3 is a rear elevation view of the present embodiment;

FIG. 4 is a left side elevation view of the present embodiment, the right side being a mirror image thereof;

FIG. 5 is a top plan view of the present embodiment; and,

FIG. 6 is bottom plan view of the present embodiment.

The broken lines shown in the drawings illustrate portions of the visor mounted eyewear that form no part of the claimed design.

1 Claim, 4 Drawing Sheets(56)
